UNITED STATES PATENT OFFICE.

FRANK K. WAY, OF DAYTON, AND WILLIAM T. PARKER, OF SPRINGFIELD,
OHIO.

TOY.

SPECIFICATION forming part of Letters Patent No. 403,232, dated May 14, 1889.

Application filed September 21, 1888. Serial No. 286,046. (No model.)

To all whom it may concern:

Be it known that we, FRANK K. WAY, of Dayton, Montgomery county, and WILLIAM T. PARKER, of Springfield, Clark county, Ohio, 5 both citizens of the United States, have invented certain new and useful Improvements in Toys, of which the following is a specification.

Our invention relates to improvements in 10 toys, the object of our invention being to provide a toy of novel construction adapted to be used as a hoop, and also partaking of the nature of a top.

Our invention consists in the constructions 15 hereinafter described, and pointed out in the claims.

In the accompanying drawings, which form a part of this specification, Figure 1 is a perspective view of a toy embodying our invention, 20 showing the same provided with a handle. Fig. 2 is a side elevation of the same without the handle. Fig. 3 is a partial sectional elevation view taken through the center, showing the manner of attaching the pivots or hubs on the handle, which also partake 25 of the nature of bells. Fig. 4 is a detail view of the handle.

Like parts are indicated by similar letters of reference throughout the several views.

30 In the said drawings, *a* represents a hoop, preferably of resilient metal—such as iron or steel—circular in cross-section. Located in the center of the hoop and suspended therefrom by small resilient wires *b* is a star, *c*, the resilient wires *b* extending from each point of the star to the hoop, said wires being secured at either end by passing through small openings, respectively, in the points of the star and in the body of the hoop. The openings in the hoop pass transversely through the body of the same, so that the outer periphery is left free and unencumbered. The star is made of thin sheet metal, and is 35 preferably painted in different colors, as indicated in the tinting of the drawings, the colors red, white, and blue being preferred. At the center of the star, which is also the center of the hoop, we place two round bells, *d d'*, one on either side of the star, as indicated. These bells consist of the ordinary 40 spherical bell having a small rolling ball, *e*,

therein. One of these bells is provided with a stud, *e'*, screw-threaded and adapted to fit in an opening correspondingly screw-threaded in the other. The stud *e'* is passed through 55 a small opening in the center of the star and secured in the other bell, the inner portions of the bells being thus brought firmly against the star.

A toy as thus described is adapted to be 60 used as an ordinary trundling-hoop. The centrally-located star *c*, being suspended by the small resilient wires *b*, appears when the hoop is in revolution to be revolving in mid-air, the wires becoming by the process of rotation invisible. The rolling balls *e* in the 65 bells *d d'* continue to sound, thus producing a very attractive amusement for children.

If a smaller size hoop is used, or for hoops to be used by small children, we preferably 70 provide a handle, *f*. This handle preferably consists of a single piece of wire twisted to form the bifurcated extremity or prongs *f'*, each of the prongs having at the end a circular opening, *f''*, adapted to fit over the inner portion, *g*, of the bells *d d'*, this portion *g* being formed in the nature of a hub, on which the bearings of the handle are adapted to turn.

When formed without the handle, the toy 80 is adapted to be used as a top by spinning the same upon the spherical portion of either one of the bells *d* or *d'*, and when started it will remain in motion for several minutes, the effect being much the same as when rotated 85 on the periphery of the wheel in a vertical position.

Having thus described our invention, we 90 claim—

1. A hoop having a centrally-located star 90 suspended at the center of said hoop by means of small resilient wires and spherical projecting bells secured rigidly to either side of said star at the center, substantially as set forth.

2. The combination, with a hoop having a 95 centrally-located star suspended at the center by resilient wires, of the spherical projecting bells secured rigidly to either side of said star, and a handle journaled on the inner portion 100 of said bells and projecting beyond the periphery of said wheel, substantially as specified.

3. A hoop of resilient metal, having the cen-

trally-located star suspended therefrom by means of resilient wires which pass transversely through the body of said hoop, leaving the periphery free, and projecting bells at the 5 center of said hoop, one of said bells being provided with a screw-threaded stud and the other being provided with an opening adapted to screw onto said stud, substantially as specified.

In testimony whereof we have hereunto set 10 our hands this 17th day of September, A. D. 1888.

FRANK K. WAY.
WILLIAM T. PARKER.
